UNITED STATES PATENT OFFICE.

WILLIAM B. BLAKE, OF BEDFORD, OHIO.

VAPOR-BURNER.

SPECIFICATION forming part of Letters Patent No. 254,911, dated March 14, 1882.

Application filed January 20, 1882. (No model.)

To all whom it may concern:

Be it known that I, WILLIAM B. BLAKE, of Bedford, in the county of Cuyahoga and State of Ohio, have invented certain new and useful Improvements in Vapor-Burners; and I do hereby declare the following to be a full, clear, and exact description of the invention, such as will enable others skilled in the art to which it pertains to make and use it, reference being 10 had to the accompanying drawings, which form part of this specification.

My invention relates to an improvement in vapor-burners; and it consists in making the slit in the burner-tip slightly deeper on one 15 side than the other, so that a portion of the flame which produces the light will be diverted so as to heat the inlet-tube, and thus to vaporize the oil, and that without in any manner interfering with the form of the blaze or the 20 brilliancy of the light produced.

The object of my invention is to dispense with the usual subsidiary jet, and with the tubes which conduct a portion of the gas to another part of the burner for the purpose of 25 forming a subsidiary jet, and thus cheapen and simplify the burner in every way.

Figure 1 is a side elevation of my invention complete. Fig. 2 is a vertical section of the same.

30 A represents a burner of any desired shape, size, or construction, upon the top of which is applied the usual tip, B. The inlet-tube through which the fluid or vapor is conducted to the burner is cast in a single piece with the vaporizing-tube D, and the upper portion of the inlet-tube rises almost to the top of the tip, and almost in contact therewith. Formed upon the top of this inlet-tube, where it bends downward, is a deflector, G, the inner edge of which 35 bears against the gas-tip, as shown. The slit cut in the gas-tip is cut deeper on the side which is next to the deflector, so that the slit will extend slightly below it. When the gas 40 is lighted it escapes through the tip and produces the usual illuminating-flame, while from that portion of the slit which extends below the inner edge of the deflector a portion of the gas escapes, and is carried by the deflector outward along the sides of the inlet-pipe. This 45

gas which passes under the deflector, being lit 50 at the same time that the body of the gas is, forms a jet for the purpose of heating the tube and vaporizing the fluid.

It will be seen that by this construction the usual flame is produced without in any manner interfering with its symmetry or brilliancy, and that a subsidiary portion of this main flame is diverted for the purpose of heating the inlet-tube without in any manner interfering 55 with the symmetry of the blaze.

By the construction above described it will be seen that all tubes for conveying gas to another part of the burner for the purpose of forming a jet for heating or vaporizing the fluid, all hoods, and other such devices as have 65 heretofore been employed for forming a subsidiary jet are entirely done away with, and that the main flame is made to furnish not only the light but the means of vaporizing the fluid.

Having thus described my invention, I 70 claim—

1. In a vapor-burner, a tip having its slit cut deeper upon one side than the other, in combination with a deflector which is placed 75 upon the inlet-pipe, substantially as shown.

2. The combination of a vapor-burner with a deflecting device, the parts being so arranged that a portion of the gas which is escaping from the tip will be deflected without impairing 80 the symmetry of the flame for the purpose of vaporizing the fluid, substantially as described.

3. The combination of the inlet-pipe provided with a deflector which has its inner edge 85 to extend inward toward or against the side of the tip, the vaporizing-tube, and a tip which has its slit cut deeper upon the side which is next to the deflector for the purpose of producing a subsidiary jet, substantially as described.

In testimony whereof I affix my signature in presence of two witnesses.

WILLIAM B. BLAKE.
